(57) CLAIM

The ornamental design for a baby change cover for ironing table, as shown and described.

DESCRIPTION

FIG. 1 is a top, front, left-side perspective view of the baby change cover for ironing table showing my new design;

FIG. 2 is a bottom, rear, right-side perspective view thereof;

FIG. 3 is a top, plan view thereof;

FIG. 4 is a right-side elevational view thereof, the left side being a mirror image thereof;

FIG. 5 is a rear elevational view thereof;

FIG. 6 is a front elevational view thereof; and,

FIG. 7 is a bottom plan view thereof.

The broken line showing of a lifted flap, in a raised position in FIG. 1, is for illustrative purposes only and forms no part of the claimed design.
